UNITED STATES PATENT OFFICE.

LYNDON C. PALMER, OF BUFFALO, NEW YORK, ASSIGNOR TO EMPIRE STATE DRUG COMPANY, OF BUFFALO, NEW YORK.

DESIGN FOR A DISPLAY-RECEPACLE.

SPECIFICATION forming part of Design No. 37,304, dated January 24, 1905.

Application filed October 11, 1904. Serial No. 228,057. Term of patent 14 years.

To all whom it may concern:

Be it known that I, LYNDON C. PALMER, a citizen of the United States, residing at Buffalo, in the county of Erie and State of New York, have invented a new, original, and ornamental Design for Display-Receptacles, of which the following is a specification.

In the accompanying drawings, Figure 1 is a perspective view of a display-receptacle embodying my design. Fig. 2 is a perspective

view of the display-receptacle looking from another direction.

What I claim as new, and desire to secure by Letters Patent, is—

The ornamental design for a display-receptacle as herein shown. 15
